UNITED STATES PATENT OFFICE.

BISMARCK R. SCHWARZ, OF MINNEAPOLIS, MINNESOTA.

RING-SIZING TWEEZERS.

1,269,321.

Specification of Letters Patent. Patented June 11, 1918.

Application filed August 30, 1916. Serial No. 117,625.

To all whom it may concern:

Be it known that I, BISMARCK R. SCHWARZ, a citizen of the United States, residing at Minneapolis, in the county of 5 Hennepin and State of Minnesota, have invented certain new and useful Improvements in Ring-Sizing Tweezers; and I do hereby declare the following to be a full, clear, and exact description of the invention, 10 such as will enable others skilled in the art to which it appertains to make and use the same.

My invention relates to improvements in tweezers and more particularly to ring 15 sizing tweezers designed to hold and protect a ring setting and jewel from heat used in soldering, expanding or contracting the ring to change the size thereof.

To the above end, the invention consists 20 of the novel devices and combinations of devices hereinafter described and defined in the claims.

In the accompanying drawings, which 25 illustrate the invention, like characters indicate like parts throughout the several views.

Referring to the drawings,

Figure 1 is a view principally in side 30 elevation of the tweezers and illustrating the same holding a ring, some parts of the tweezers being shown in section and some parts being shown in different positions by means of broken lines;

Fig. 2 is a plan view of the tweezers, as 35 shown in Fig. 1;

Fig. 3 is a transverse section taken on the line 3—3— of Fig. 2; and

Fig. 4 is a transverse section taken on the line 4—4— of Fig. 3.

40 The legs of the tweezers are indicated by the numerals 1 and 2 and they are rigidly connected at one of their ends by rivets 3 with a spacing block 4 inserted between said legs. The legs 1 and 2 are made from 45 spring material and tend to separate at their free ends, as shown by broken lines in Fig. 1. A metal loop 5 encircles the legs 1 and 2, with freedom for longitudinal sliding movement thereon, and is provided for holding 50 the free ends of said legs together against the tension of their spring action.

Opposing holders 6 and 7 are rigidly secured, respectively, to the inner faces of the legs 1 and 2, at the outer ends thereof. The 55 holder 6 is in the form of a disk riveted to the leg 1 and has integrally formed there-

with circumferentially spaced inwardly projecting hook-like prongs, the free ends of which extend radially toward each other. The holder 7 is in the form of a cup having 60 a contracted mouth and is riveted to the prong 2.

The holder 6 is made relatively narrow, in order that the same may be inserted through a ring Z, with its prongs straddling 65 the ring at the setting thereof. Wads 8 of asbestos, cotton, or other suitable pliable material, saturated with water, are held, the one in the holder 6 and the other in the holder 7. These wads 8 are arranged to be 70 separated on the line y—y of Figs. 1 and 3. When the legs 1 and 2 are closed, the holder 6 enters the holder 7 as a box goes into its capping lid and the pliable wads 8 entirely embrace and cover the ring setting and 75 jewel and thereby protect the same from the heat used in soldering, expanding or contracting the ring Z, for the purpose of changing the size thereof.

With the loop 5 slid to the front or free 80 ends of the legs 1 and 2, the ring 7 is securely held within the holders 6 and 7, so that the same may be easily handled and, at the same time, its setting and jewel are protected from the heat. The size of the 85 connected ends of the legs 1 and 2 is such that the loop 5 cannot be removed thereover and the holders 6 and 7 prevent the removal of said loop at the other end of said legs. The peculiar shape of the holders 6 and 7 90 securely holds the wads 8 therein and permits new wads to be substituted for old ones from time to time. While the improved tweezers are illustrated and described as holding a ring to protect the setting and jewel, it is, of course, understood that the same may be used for holding various other articles to protect certain of the parts thereof from heat. 95

What I claim is:—

1. Ring sizing tweezers having a relatively small holder and a relatively large holder, and wads of pliable material applied in said holders and within which pliable material a ring setting and jewel 105 may be completely embedded under compression of said holders.

2. Ring sizing tweezers having a pair of holders, and wads of pliable material applied in said holders and within which pliable material a ring setting and jewel may 110 be completely embedded under compression

100

110

of said holders, one of said holders being cup-like and the other thereof having a plurality of hook-like prongs.

3. Ring sizing tweezers having a pair of 5 holders, and wads of pliable material applied in said holders and within which pliable material a ring setting and jewel may be completely embedded under compression of said holders, one of said holders being 10 cup-like with a contracted mouth and the other thereof having a plurality of hook-like prongs.

4. Ring sizing tweezers having a rela-

tively small holder and a relatively large holder movably connected, and wads of pliable material applied in said holders and within which pliable material a ring setting and jewel may be completely embedded under compression of said holders. 15

In testimony whereof I affix my signature 20 in presence of two witnesses.

BISMARCK R. SCHWARZ.
